UNITED STATES PATENT OFFICE.

SIEGFRIED ROSENZWEIG, OF NEW YORK, N. Y.

VALVE-GEAR.

1,323,789.

Specification of Letters Patent.

Patented Dec. 2, 1919.

Application filed March 4, 1919. Serial No. 280,550.

To all whom it may concern:

Be it known that I, SIEGFRIED ROSENZWEIG, a citizen of the United States, residing in New York city, in the county and State of New York, have invented a new and useful Improvement in Valve-Gears, of which the following is a specification.

My invention relates to, and is an improvement on, the form of valve gear construction which is the subject of my application for Letters Patent Serial No. 267,620 filed December 20, 1918. It will first be described in connection with the accompanying drawing, and will then be more particularly pointed out in the claim.

In the drawing—

Figure 1 is a transverse section of a steam engine with my improvement applied thereto, the plane of section being in the vertical plane of the axis of the valve chamber or chest; and,

Fig. 2 is a section on line 2—2 of Fig. 1, with a slight modification in the construction of the valve chamber or chest and sectional valve cage from what is represented in Fig. 1.

A is a steam cylinder; B a cylindrical valve chamber or chest extending crosswise of, and substantially tangential to the steam cylinder; C an externally cylindrical valve cage removably fitted and held in the valve chest B which is machined out to receive it and is formed with an internal shoulder b against which the cage brings up when inserted in place in the valve chest; D a clearance chamber in the cage; V a double seated puppet valve within the clearance chamber engaging corresponding seats in the clearance chamber; e the inlet port through which steam is admitted into the steam cylinder; x an axial tubular guide for the valve spindle w cast in one with the rear wall of the clearance chamber.

The cage C at its end opposite to that which contains valve V extends out through and beyond the open end of the valve chest and is formed with an annular laterally projecting flange c which overlaps the face of a corresponding flange d on the end of the steam chest, the two being secured together by bolts and nuts f.

Diametrically crosswise of the cage near its open end is a tubular divided bearing g for the reciprocating valve operating cam or tappet shaft S, composed of two portions which extend in axial alignment with one

another from opposite sides of the cage toward its center but do not meet, there being an interval between their inner opposed ends which is spanned by another tubular bearing h cast in one with the divided bearing g and cage C, having its bore in axial alignment with that of the spindle guide w, and designed to receive the roller carrier i on the end of the valve spindle, said roller-carrier having mounted on it the anti-friction roller k which protrudes into the open space between the two ends of the divided bearing g in position to be acted on by the longitudinally reciprocating cam or tappet shaft S. The exterior opposite ends of the divided bearing g projects laterally through guide slots g' in the walls of the valve chest B.

As thus far described the construction does not differ materially from that which is described and shown in my aforesaid application Serial No. 267,620, filed December 20, 1918. The material difference between the two is that in the structure described and shown in my previously filed application, the cage is a one piece casting, whereas in the improved structure, subject of my present application, the cage is composed of a plurality of tubular sections separably fitted, and adapted to be connected, together, one end section formed with the clearance chamber and valve seats therein to coöperate with the valve contained therein, and the opposite end section containing the bearings for the valve operating cam shaft, and the valve spindle roller-carrier respectively.

In the particular embodiment of my improvement illustrated in the drawings, the cage is composed of two tubular sections, c², c³ separably fitted together end to end in the cylindrical valve chest B, the interior of which is machined out accurately to receive them, the one section c³ formed with the clearance chamber D the valve seats therein to coöperate with the seating faces of the valve V, and the valve spindle guide x, the other section formed with the divided bearing g for the cam operating shaft S and the tubular bearing h for the valve spindle roller-carrier i. The last named cage section has the annular flange c on that end of it which projects beyond the valve chest B, which flange overlaps the correspondingly flanged end of the steam chest to which it is united by bolts and nuts f. The meeting ends of the two sections are internally flanged as at c', to receive securing devices

such as the bolts and nuts c^5 to detachably connect them.

This construction is advantageous especially for large engines in which the cage, 5 if a single piece casting is so large as to be unwieldy and difficult to handle. By casting it in a plurality of sections this difficulty is avoided. The sections after being separately cast, have their flanged meeting ends faced 10 and are then assembled end to end and bolted together so as to form in effect one complete casting for the purpose of machining all the parts together. When thus machined and provided with its appropriate 15 fittings the sectional casting can be inserted and put in place in the valve chest, either as a single casting, or in separate sections which may be bolted together or not as preferred, the cage, in either event being held 20 in secure position by the shoulder b at one end and the bolts and nuts at the other.

In Fig. 1 there is a jog in the steam chest B at the point where the two cage sections meet, forming a shoulder b^2 which is ever- 25 lapped by the flanged meeting ends c^4 of the sections, as shown. The diameter of the part of the steam chest B which receives the inner cage section is slightly less than that of the part which receives the outer cage sec- 30 tion, and the sections are of proportionately varied dimensions. In Fig. 2, the two sec- 35 tions are of the same diameter and there is no shoulder b^2 in the valve chest. The latter construction is on the whole preferred. Gas- kets m of copper wire are provided at the joints between the sections and other

proper points as shown. The construction described permits the outer end section of the cage to be removed leaving the inner end section with its contained fittings in 40 place, if for any cause—for example to get at the valve controlling spring—it becomes necessary to reach the interior of the cage.

In the case of unusually large engines it may become necessary to introduce one or 45 more additional sections as spacers between the end cage sections as will be understood without further explanation.

What I claim herein as new and desire to secure by Letters Patent is: 50

The combination with a steam cylinder and steam chest of a valve cage composed of a plurality of tubular sections separably fitted together, and removably held in a seat of corresponding shape in the valve chest, 55 the inner end cage section being formed with a clearance chamber to contain the valve, seats in said chamber to coöperate with the seating faces on the valve, and a tubular spindle guide for the passage and support of, 60 the valve spindle, and the outer end section being provided with a bearing for the operating cam-shaft extending diametrically crosswise of the open end of said section, and with a central tubular bearing in axial 65 alignment with the spindle guide, for the support and guidance of the roller end of the valve spindle which engages the operating cam-shaft.

In testimony whereof I affix my signature. 70

SIEGFRIED ROSENZWEIG
